UNITED STATES PATENT OFFICE.

JAMES B. LAMONT AND FERDINAND A. LORENZ, OF SAN FRANCISCO, CALIFORNIA.

DRAFT DEFLECTOR FOR WINDOWS.

Application filed January 31, 1925. Serial No. 6,093.

To all whom it may concern:

Be it known that we, JAMES B. LAMONT and FERDINAND A. LORENZ, citizens of the United States, and residents of the city and county of San Francisco, and State of California, have invented certain new and useful Improvements in Draft Deflectors for Windows, of which the following is a specification.

This invention relates to draft deflectors for windows, and is particularly adaptable to the ordinary double-sash windows most commonly used, though it may be used to advantage with some types of reversible windows.

Our invention comprises a pair of suitable frames carrying panes and adapted to be held in slidable relationship by means of guideways borne by one or the other of the frames, permitting a sliding fit admitting of a telescopic movement in adjusting for different width windows. These frames are adapted to carry end brackets which form supports of triangular shape adapted to fit between the casement uprights and securely hold the frames in position by means of slots engaging screws, or the like, borne by the uprights. When in position, the bottoms of the frames rest upon the window sill and the brackets support the frames at the proper inclination within the room to deflect entering air currents upwardly into the room, when the lower window sash has been raised a required distance above the window sill. The frames may be constructed of metal, or of wood, or any well known fibre-board, or other material adapted to carry window panes of transparent, translucent, opaque, or other character.

A primary object of my invention is to provide a draft deflector of the type designated of simple design, cheaply constructed, and of a character that may be easily and readily placed in position and adjusted to width without resorting to cutting or fitting.

A further object is to provide a construction in draft deflectors that is not alone adjustable as to width, but, also, as to height and its inclination to entering air currents.

The invention is fully illustrated in the accompanying drawings, in which:

Figure 1 is a vertical sectional view of an ordinary window casement, showing our invention in place and resting in inclined po-

sition upon the window sill, with the lower sash raised slightly above the sill for the admission of fresh air;

Figure 2 is a side elevation, showing the device as it would appear removed from the window casement, with its frames in telescoped relationship;

Figure 3 is a top plan view, as shown in Figure 1 and indicated by the arrow in that figure; and

Figure 4 is a perspective view, showing the frames in extended relationship, or, as they would appear when in readiness for insertion between the casement side-members.

Referring more particularly to the drawings, our invention is comprised of a pair of small frames 1 and 2, in the form of miniature window frames, adapted to carry window panes 3 and 4, the frame end-pieces 5 and 6 being offset with relation to their respective connecting pieces, so that they may lie in a common plane in either telescoped or extended position.

The frames 1 and 2 are adapted to slide one upon the other, with the frame 2 provided with channelled guideways 7 and 8 secured to its upper and lower edges by means of screws, or the like, 9 and 10, and adapted to receive the frame 1, as shown in Figures 1 and 4; triangular brackets 11 and 12 are respectively secured to the frame end-pieces 5 and 6 of the frames 1 and 2 by means of nails, or the like, 13, and extend at right angles to said frames and are provided at their outer edges with obliquely arranged attaching slots 14 and 15 adapted to engage screws, or the like, 16, placed at predetermined positions upon the inner faces of the casement uprights 17. A small pin 18, or the like stop, may be placed on the inside of the inner end-piece of the frame 1, after the frames have been assembled, and in position to engage the inner edge of the inner end-piece of the frame 2, to prevent the frames, at any time, being pulled entirely apart.

It will be noted, with reference to Figure 1, that the inclination of the deflective surface of the device, when in position between the casement uprights and resting upon the sill, is such that air currents entering below the upraised sash will be deflected upwardly in the direction indicated by the arrows, thus obviating the direct currents or horizontally directed drafts, so vexatiously annoying in

offices in scattering papers and documents, in addition to being prolific agents in causing congestions, colds, and other ailments.

The inclination of the deflective surface 5 may be varied, or adjusted, to any desired angle of inclination, by simply varying the shape of the end brackets 11 and 12, or the position and direction of the slots 14 and 15 relative to the attaching screws 16.

10 The device is intended to rest snugly upon the sill 19, to form an air-tight fit between the frames 1 and 2 and said sill, and the lower sash of the window should not, ordinarily, be raised above the position shown in 15 the drawings—that is, relative to the top edge of the deflector.

The invention's predominating features are its adaptability to any ordinary window; its extensibility, permitting adjustment laterally to fit it to windows of varying widths; and its simplicity and the ease with which 20 it may be attached to any window casement.

Having thus illustrated and described our invention in its preferred form, we claim, 25 and desire to secure by Letters Patent:

In a device of the character described, comprising, in combination with a window casement, attaching-screws mounted in the casement frame, and a pair of slideable frames carrying window panes, said frames comprising end pieces and connecting pieces, triangular end brackets carried by the outer end pieces, said outer end pieces being offset with respect to their respective connecting pieces and thereby adapted to lie in a common plane when telescoped or extended, one of said frames being provided with channelled guide-ways secured to its upper and lower edges to receive the other of said frames, one of said frames being provided 30 with a stop-pin adapted to extend into the path of the end-piece of the other frame to limit the movement of said frames relative to each other, said triangular brackets being provided at their upper edges with obliquely 35 arranged slots open at their outer ends and adapted for adjustable engagement with said attaching-screws.

JAMES B. LAMONT.
FERDINAND A. LORENZ.
